The ornamental design for an in-line lawn chemical injector, as shown and described.

DESCRIPTION

FIG. 1 is an exploded front, top and side perspective view of the in-line lawn chemical injector embodying the present invention;

FIG. 2 is a front elevational view thereof, the rear being a mirror image;

FIG. 3 is a side elevational view thereof, the side opposite being a mirror image of the side shown in FIG. 3;

FIG. 4 is a top plan view thereof; and,

FIG. 5 is a bottom plan view thereof.
